CLAIM

The ornamental design for an absorbent article package, as shown and described.

DESCRIPTION

FIG. 1 is a perspective front view of an absorbent article package embodying the new design;

FIG. 2 is a front view of the design shown in FIG. 1;

FIG. 3 is a right side view of the design shown in FIG. 1;

FIG. 4 is a back view of the design shown in FIG. 1;

FIG. 5 is a left side view of the design shown in FIG. 1;

FIG. 6 is a top view of the design shown in FIG. 1; and,

FIG. 7 is a bottom view of the design shown in FIG. 1.

FIG. 8 is a perspective front view of another embodiment of an absorbent article package embodying the new design;

FIG. 9 is a front view of the design shown in FIG. 8;

FIG. 10 is a right side view of the design shown in FIG. 8;

FIG. 11 is a back view of the design shown in FIG. 8

FIG. 12 is a left side view of the design shown in FIG. 8;

FIG. 13 is a top view of the design shown in FIG. 8; and,

FIG. 14 is a bottom view of the design shown in FIG. 8.

The broken line showing the package surfaces depicts environment and forms no part of the claim.

1 Claim, 8 Drawing Sheets
